LOOSE-LEAF BINDER

Emil N. Farkas, Chicago, Ill., assignor of one-half
to Frank F. Farkas, Chicago, Ill.

Application December 10, 1938, Serial No. 244,951

5 Claims. (Cl. 129—1)

This invention relates to new and useful improvements in loose-leaf binders and particularly of plastic material or the like.

Binders of plastic material are usually made in the form of a comb rolled up along its longitudinal axis with the teeth overlapping the back of the comb. The material is sufficiently resilient to permit the operator to pry open the teeth for insertion through the marginal perforations of the leaves. After assembly the teeth are placed on the inside of the roll.

I have found that when such binders are used to hold together a large number of heavy leaves, they have a tendency to open and catch on the leaves. This is true particularly for plastic materials having slick surfaces.

To overcome this, in accordance with the present invention, I indent, serrate or roughen the overlapping surfaces of the roll of plastic binders whereby it will resist the strains to which it may be subjected during use.

Three embodiments of the invention are illustrated in the perspective views (partly in section) of Figs. 1-3 of the drawing, Fig. 1 illustrating a serrated or roughened, and Figs. 2 and 3 two types of indented overlapping surfaces.

As shown in Fig. 1, the binder consists of a comb having a back 1 and teeth 2. The comb is rolled up along its longitudinal axis so that the teeth 2 overlap the back 1. To guard the comb from easily pulling apart, I roughen the inner surfaces of the teeth as indicated at 3, and those portions of the back 1 which contact with the teeth, as indicated at 4. I have found that placing the teeth 2 on the outside of the roll produces better results than when they are on the inside of the roll.

The operator may pry the roll open, pass the teeth 2 through the marginal perforations of the leaves, and then snap them in place.

In the modification shown in Fig. 2, each tooth 10 is perforated at 11 and the material cut out bent down as shown at 12. The projection 12 in each tooth 10 registers with a corresponding perforation 13 in the overlapping portion of the back 15. The material struck up to form perforation at 13 is bent up into registry with the perforation 11 in the tooth 10.

In the arrangement shown in Fig. 3, the fingers 20 are indented as shown at 21 and registering projections 22 are formed in the contacting portion of back 23.

In all the three embodiments the operator may pry the cylinder open without the need of special tools and without mutilating the structure, and yet the teeth will be held from sliding open even when used on heavy books. The teeth and the back are thus held against relative longitudinal movements but are free to move transversely with respect to one another.

What I claim is:

1. In a loose-leaf binding device, a comb of resilient molded composition having back and teeth rolled into a cylinder of predetermined diameter the longitudinal axis of which is parallel with the back, the teeth being transverse thereto and overlapping the back, cooperating projections and recesses formed in the back and teeth which interlock when the cylinder is of said predetermined diameter, the projections and recesses being shaped to lock the cylinder against enlargement of its diameter in response to forces normally applied thereto and unless the teeth are pried laterally away from the back, but when the cylinder is radially compressed the projections will spring out of the recesses and permit the rolling up of the cylinder into one of smaller diameter.

2. The binding device defined in claim 1 and in which the projections are bent out portions and the cooperating recesses are openings.

3. The binding device defined in claim 1 and in which the projections are bent down portions of teeth and the cooperating recesses are openings in the back.

4. The binder defined in claim 1 and in which a bent down portion of each tooth engages a corresponding opening in the back, and a bent up portion in the back formed adjacent each opening engages an opening formed in each tooth adjacent the bent down portion.

5. The binder defined in claim 1 and in which the projections and recesses are in the form of interlocking corrugations formed in the back and teeth.

EMIL N. FARKAS.
